UNITED STATES PATENT OFFICE

CHARLES CLINTON ALVORD, OF WORCESTER, MASSACHUSETTS, ASSIGNOR TO WORCESTER LOOM WORKS, OF WORCESTER, MASSACHUSETTS

GRIPPER LOCKING AND UNLOCKING MECHANISM

Application filed June 15, 1929. Serial No. 371,152.

This invention relates to tuft weaving looms and particularly to that type of carpet loom which employs a series of grippers to transfer the pile tufts from the source of supply to the fell of the fabric. The source of supply may be either tuft frames or jacquard controlled yarn carriers, the former method being illustrated in the patent to Clinton Alvord, No. 1,436,619.

It is the object of the present invention to provide a gripper locking and unlocking mechanism which will function satisfactorily at the relatively higher speeds at which carpet looms now run.

A second object is to provide simple and rapid means of disconnecting the motion whenever required.

A further object is to provide a mechanism of great mechanical efficiency which will provide great gripping pressure for holding the tuft yarn with relative low pressure on the working parts.

With the above and other objects in view my invention consists in the arrangement and details of construction, disclosed in the drawings and specification and then more particularly pointed out in the appended claims.

In the drawings Fig. 1 represents a side elevation in cross section of my improved mechanism taken on line A—A of Fig. 2.

Fig. 2 is a front elevation of the same;

Fig. 3 shows the grippers at the pile seizing position just as they have been locked and

Fig. 4 illustrates the mechanism at the instant of unlocking the grippers at the pile releasing point.

The loom frame 1 has journaled therein gripper fulcrum shaft 2 having castings keyed thereon, at suitable intervals across the loom, one of which is shown at 3. These castings provide bearings for the wing shaft 4 and a seat for the rectangular gripper holding bar 5. Grippers 6 are fastened to the bar as in common practice. The movable jaw 7 of each gripper terminates in a ball-shaped end 8 which rests in the pocket piece 9 staked into the oscillatory wing shaft 4. The wing shaft bearings on castings 3 are

opened up as at 10 in Fig. 1 so as to permit the shaft to oscillate sufficiently to open and close the grippers.

The motion to lock and unlock the grippers originates with cam lever 11 operated by cam 12 keyed to the main cam shaft 13 of the loom. Connector 14 fastened on a stud at the end of the cam lever extends upward to one arm 15 of a bell crank lever freely rotatable on rock shaft 16 journaled in the loomsides. The other arm 17 of the bell crank lever has fulcrumed thereon pawl 18 which is allowed to drop freely into the tooth of ratchet 19 as shown in Fig. 1. Ratchet 19 is keyed to shaft 16 and thus, whenever cam lever 11 is forced downwardly by cam 12, the motion will be transmitted by connector 14 to the bell crank lever and thence by the pawl 18 and ratchet 19 to the shaft 16. In case it is desired at any time to interrupt these periodical movements of shaft 16 due to the rotation of the cam, I provide a flexible connection 20 fastened to pawl 18 and running over pulleys or by other suitable means not shown to some location convenient for the weaver who can, by pulling the pawl out of engagement with the ratchet tooth, quickly and easily interrupt the train of movement. Such a condition might exist when weaving headings on a rug at which time no pile is being inserted by the grippers and it might prove desirable to stop their continued opening and closing. Ratchet 19 has a downwardly extending arm 36 to which spring 37 is attached, in order that shaft 16 be thereby returned to its inoperative position, further rotation in that direction being prevented by the abutting of screw 38 against lug 39 which projects outwardly from the frame. By properly adjusting the screw it will be seen in Fig. 1 that sufficient clearance is provided between pawl 18 and the tooth of ratchet 19 to allow the pawl to be raised out of, or lowered into engagement therewith whenever the cam roll of lever 11 is in the dwell of cam 12.

There is a lever 21 keyed on shaft 16 and equipped with a freely turning roll 22. Sector gear 23, freely pivoted on gripper fulcrum shaft 2, has an extended arm 24 which is contacted and moved counterclockwise by

roll 22 whenever lever 21 swings upward due to a rise on cam 12. Another sector gear 25 is keyed to wing shaft 4, the teeth of the two gears being in mesh. Thus whenever the 5 wing shaft is moved clockwise by the upward thrust of roll lever 21 the grippers will close. Collar 23a prevents endwise slippage of gear 23.

When the cam roll on lever 11 has been 10 forced to its extreme down position by rise 26 on cam 12 the grippers will be fully closed and the various parts will appear as in Fig. 3, bearing 3 being omitted for the sake of clarity. In order to retain the grippers closed, 15 or locked, I provide pawl lever 27 keyed to shaft 2 and equipped with a pawl 28 which can snap into the recess back of tooth 29 on gear 23 whenever the gear has been rotated by lever 21 to the position shown in the above 20 mentioned figure. The pawl is urged into engagement by a spring not shown. Lever 21 may now drop back to its position in Fig. 1 but the grippers will remain locked due to 25 pawl 28 contacting tooth 29.

After drawing off the proper length of pile 30 yarn from the source of supply the grippers descend to their pile releasing position at the shed as shown in Fig. 4. Any of the well-known mechanisms for raising and lowering 35 the grippers may be employed such as the rack and gear motion shown in Fig. 1 of the Clinton Alvord Patent #1,436,619. At this point it will be noted that screw 30 on lever 21 is in position to abut offset tail 31 on 40 pawl 28 when the small rise 32 on cam 12 contacts and operates the cam roll. The continued downward movement of the cam lever forces the screw 30 smartly against the offset tail 31 thus throwing the pawl out of engagement with tooth 29. The grippers are now 45 free to open and to assure their doing so with great rapidity, I employ spring 33 fastened at one end to a pin in gear 25 and at the other, or fixed end, to extension arm 34 on pawl lever 27. In many of the mechanisms heretofore employed it has been customary to allow 50 a knocking off bunter corresponding to the screw 30 to contact and force out of engagement a trigger which, when free, was compelled to slide by the bunter as the grippers opened. The friction caused by such an arrangement slows down the opening of the grippers and results in uneven pile. Conditions varied from day to day depending upon 55 the amount of lubricant present on the contacting surfaces. It will be noted in the present arrangement, however, that the opening screw 30 is not thus in contact with any part of the mechanism which is rotated by the action 60 of spring 33 during the opening of the grippers. Once the pawl has been forced out clear of tooth 29 there is no drag imposed on the rapidly rotating parts. The grippers continue to open until screw 35 which is threaded 65 in an offset on extension arm 34 contacts gear

23 as shown clearly in Fig. 1. The use of this check screw prevents straining of the pivoted joints of the individual grippers through excessively wide opening such as occurs when no stop is provided. 70

I am aware that various changes may be made in the construction and arrangement of the parts without departing from the scope of this invention as expressed in the claims. I do not wish, therefore, to be limited to the 75 construction I have herein shown and described, but

What I do claim and desire to secure by Letters Patent of the United States is:

1. In a loom for weaving tufted fabrics, a 80 series of grippers having moveable jaws, a shaft operatively contacting said jaws to open and close them, a quick-releasable catch to retain the jaws in closed position, a gear on said shaft and mechanism adapted to engage said gear whereby said shaft may be operatively oscillated. 85

2. In a loom for weaving tufted fabrics, a gripper fulcrum shaft, a gripper holding bar 90 secured thereto, a wing shaft adapted to be operatively oscillated to open and close a set of grippers mounted on said bar, a sector gear on said wing shaft, a mating gear loosely mounted on said fulcrum shaft and means 95 to move said mating gear whereby said grippers are opened or closed. 95

3. In a loom for weaving tufted fabrics, a gripper fulcrum shaft, a wing shaft adapted 100 to be operatively oscillated to open and close a set of grippers, a sector gear on said wing shaft, a mating gear loosely mounted on said fulcrum shaft, means to move said mating gear to close the grippers, a check to retain the grippers in closed position and mechanism adapted to contact and release said check said mechanism being so arranged that no relative motion occurs at the point of contact while the grippers are opening whereby the speed of opening is increased. 105

4. In a loom for weaving tufted fabrics, a 110 series of grippers provided with movable jaws, an arm for closing the jaws, a catch to retain them in closed position, a trigger shaft provided with a lever having a roller and an adjustable knock-off screw and means to periodically oscillate said trigger shaft, said roller contacting said arm as said shaft oscillates to close the jaws and said screw contacting said catch as said shaft oscillates to 115 open the jaws. 115

5. In a loom for weaving tufted fabrics, a 120 series of grippers provided with movable jaws, an arm for closing the jaws, a trigger, a trigger shaft provided with a lever fast thereon equipped with a roller adapted to provide rolling contact with said arm and means operatively oscillating said trigger shaft to effect rolling contact between said arm and said roller to close the jaws, said 125 130

trigger being adapted to releasably lock the jaws.

6. In a loom for weaving tufted fabrics, a set of grippers, means to open and close said grippers, mechanism to actuate said means and a device interposed between said means and said mechanism comprising a single tooth ratchet and driving pawl therefor adapted to be manually moved out of contact with said ratchet whereby the means to open and close said grippers is rendered inoperative.

7. In a loom for weaving tufted fabrics, a gripper holding bar, wing shaft mechanism adapted to be actuated to close and open a set of grippers mounted on said bar, a releasable catch to retain the grippers in closed condition, and an oscillating lever provided with a roller and an adjusting bunter, the roller serving to effect operative contact between the lever and the wing shaft mechanism to close the grippers and the adjusting bunter contacting said catch to permit the grippers to open.

In witness whereof I have hereunto set my hand this 13th day of June, 1929.

CHARLES C. ALVORD.
